UNITED STATES PATENT OFFICE

123,814

DESIGN FOR A COMBINED WATCH AND BRACELET OR SIMILAR ARTICLE

Max Megur, New York, N. Y.

Application October 25, 1940, Serial No. 96,069

Term of patent 3½ years

To all whom it may concern:

Be it known that I, Max Megur, a citizen of the United States, residing in the city of New York, county of Bronx, and State of New York, have invented a new, original, and ornamental Design for a Combined Watch and Bracelet or Similar Article, of which the following is a specification, reference being had to the accompanying drawing, forming part thereof.

Figure 1 is an edge view of a combined watch and bracelet or similar article showing my new design.

I claim:

The ornamental design for a combined watch and bracelet or similar article, as shown.

MAX MEGUR.
